UNITED STATES PATENT OFFICE.

MATHEW JICHA, OF BRIDGEPORT, OHIO.

RAILWAY RAIL MOUNTING.

Application filed April 1, 1922. Serial No. 548,849.

To all whom it may concern:

Be it known that I, MATHEW JICHA, a citizen of the United States of America, and resident of city of Bridgeport, county of Belmont, and State of Ohio, have invented certain new and useful Improvements in Railway Rail Mountings, of which the following is a specification.

This invention relates broadly to railway rail mountings, and more specifically to a crosstie and means for fastening rails thereon.

The primary object of the invention is to provide a simple and durable crosstie having efficient means for rigidly fastening rails thereto without the use of spikes or bolts.

A further object is to provide a combination concrete and metal crosstie having associated therewith fastening or attaching means which, following application, will require no adjustment or resetting during the life thereof.

With these and other objects in view, the invention resides in the features of construction, arrangement of parts and combinations of elements which will hereinafter be fully described, reference being had to the accompanying drawings, in which—

Figure 1 is a top plan view of an end portion of the crosstie with the rail-fastening devices mounted in position thereon;

Figure 2 is a side elevation of the same showing a rail mounted in place;

Figure 3 is an end elevation of the invention as shown in Fig. 1;

Figure 4 is a view similar to Fig. 1, showing a slightly modified form of clamp;

Figure 5 is a similar view showing another modified form of the rail fastening means, and—

Figure 6 is an end elevation of the structure shown in Fig. 5.

Referring to said drawings, A indicates the crosstie which consists of a concrete body or core 1 encased within a sheath or shell 2, preferably of sheet metal. While said crosstie may be of other form in cross section, it is at present preferred that the under surface thereof shall be flat, that the sides thereof shall be substantially vertical and that the top thereof shall be convex, as shown.

Formed in the upper face of the crosstie adjacent its opposite ends and separated by a suitable distance, according to the gauge of the trackway to be laid, are transverse channels 3 of suitable depth and having flat

bottoms, said channels being of greater width at their bottoms than at their tops to provide opposite undercut lips 4. Mounted upon the flat bottom of each channel is a transversely disposed leveler plate 5 designed to complement a similarly disposed clamping plate 6 by means of which one edge of the base of a track rail 7 superposed upon said plates is secured against movement. Said plates 5 and 6 are of equal thickness and, consequently, together form a level seat for the rail base. Said plates together have a width closely approximating that of the bottom of the channel 3 upon which they rest, and the rail 7 is disposed in a position in which one side of its base is received closely beneath the adjacent lip 4, while the opposite edge is closely embraced by a base-overlying tongue 8 struck up from the plate 6.

The leveler plate 5 has its opposite ends 9 turned downward into closely seating relation to the sides of the crosstie, thereby to prevent longitudinal shifting of said plate.

The clamping plate 6 is slit inward from its outer edge at a point adjacent to one end thereof, and the portion intermediate the slit and said end is turned downward to form a lug 10 which, in the properly seated position of said plate, has its inner edge in abutting relation to the adjacent side of the crosstie. A key or pin 11 is directed downward through the opposite end portion of said plate 6 so as to abut the opposite side of the crosstie, said lug and said key or pin serving to prevent shifting of said plate.

In practice, the leveler plate 5 is first placed in its proper place in the channel 3 of the crosstie, after which the rail 7 is introduced in said channel and is shifted to a position in which that edge of the base which overlies said plate is closely received beneath the adjacent overhanging lip 4. Then, the clamping plate 6 is introduced in place by driving it endwise under said rail base between the inner edge of the plate 5 and the opposite bottom edge of the channel and with the tongue 8 overlying said base. When the said plate 6 has been driven to the point at which the lug 10 engages the crosstie, the key 11 is inserted through the hole 12 provided therefor.

The plate 6^a shown in Fig. 4 is in all respects similar to the plate 6 hereinbefore described, except that two struck-up tongues 8^a are substituted for the single tongue 8.

In the modification shown in Figs. 5 and

6 is illustrated a leveler plate 5^b having its opposite ends prolonged horizontally to form extension seats 13 for underlying the rail base throughout a considerable distance on 5 opposite sides of the crosstie, said seats being designed not only to afford additional support for the rail, providing for a wider spacing of the crossties, but also to anchor the crosstie against shifting movement. 10 The opposite lateral edges of said seats 13 are turned downward and form vertically disposed wings 14 adapted to abut the opposite sides of the crosstie. The clamping plate 6^b has one end turned downward similar to the ends 9 of the plate 6 shown in 15 Figs. 1, 2 and 3.

What is claimed is—

1. A rail mounting and clamp comprising a crosstie having a transverse channel in its 20 top adjacent each end thereof, said channel being shaped to form opposite undercut lips, a clamping plate seating at one side of said channel with an edge thereof underlying one of said lips, said plate having a struck- 25 up tongue adapted to overlie an edge of the base of a rail which is seated thereon with its opposite edge closely engaged with the opposite lip, means carried by said plate

whereby the latter is secured against displacement, and a leveler plate seating upon 30 the bottom of said channel in complementary relation to said clamping plate.

2. A rail mounting and clamp comprising a crosstie having a transverse channel in its top adjacent each end thereof, said channel 35 being shaped to form opposite undercut lips, a clamping plate seating at one side of said channel with an edge thereof underlying one of said lips, a leveler plate seating at the opposite side of said channel with an edge 40 thereof underlying the other lip, said plates being complementary one to the other and forming a seat for a rail base, said clamping plate having a clamping member engaged with the overlying edge portion of 45 the rail base when the latter is positioned with its opposite edge in underlying relation to the lip which overhangs the leveler plate.

In testimony whereof, I affix my signature 50 in presence of two subscribing witnesses.

MATHEW JICHA.
